PORTABLE RADIO RECEIVER

Gilbert E. Gustafson, River Forest, Ill., assignor
to Zenith Radio Corporation, a corporation of
Illinois

Application March 11, 1944, Serial No. 526,095

2 Claims. (Cl. 250—14)

1

This invention relates to radio apparatus, and particularly to such apparatus provided with a loop antenna arranged to be used with the apparatus either mounted on the apparatus or in positions remote from the apparatus.

Portable radio receivers have heretofore been provided with loop antennae which can be used either within the receiver case or housing, or in a location remote from such case or housing, as, for example, on the window of a railroad car or other vehicle. Such an antenna when used within the receiver case or housing is much affected by proximity to metal portions of the receiver and, if the receiver case or housing is made of metal, the antenna is entirely useless when mounted inside of the housing.

It is a primary object of this invention to provide a loop antenna mounted in connection with radio apparatus in a new and improved way, whereby it may be used either when fastened to the housing or at a position remote from the apparatus housing, and when fastened to the housing is substantially unaffected by metal parts of the apparatus.

Another object of the invention is to provide an improved antenna mounting arrangement for such radio apparatus which is especially useful when the housing for the apparatus is constructed primarily of metal or conductive materials.

It is a further object of this invention to provide such an improved antenna arrangement for radio apparatus which can be readily carried while the loop antenna and radio apparatus are in operation.

The features of the present invention which are believed to be novel are set forth with particularity in the appended claims. This invention itself, both as to its organization and manner of operation, together with further objects and advantages thereof, may best be understood by reference to the following description taken in connection with the accompanying drawing in which:

Figure 1 illustrates a radio receiver incorporating this invention and arranged for operation with a loop antenna mounted on the window of a metal railroad car;

Fig. 2 shows the same receiver closed up and in inoperative condition for carrying; and

Figs. 3 and 4 are elevational views of the rear side of the loop antenna, before and after being arranged for support as shown in Fig. 1.

Figure 5 is an illustration of an operative element of the receiver of Figure 1.

Figure 6 is a partial cross-sectional view of a portion of the structure of Figure 4.

In Fig. 1, a radio receiver 10 having trapezoidal-shaped ends as shown in Figures 1 and 2 is illustrated on the seat of a railroad car or automobile. A door 11, which normally encloses the front of the receiver is illustrated in an open position, in which it lies in a vertical plane above the receiver 10. The front of the receiver 10, which is normally enclosed by the door 11, has extending therefrom control knobs 12 for the tuning of the receiver and the volume control and on-off switch combination, as well as the tuning dial 13, and is found in the apertured area 14 behind which the loud speaker is placed.

The door 14 is formed of dielectric material, such as wood, fiber or plastic, and it is supported on the housing of the receiver 10 by relatively long armed metal hinge members 15, which extend substantially at right angles to the door 11, the hinge members 15 each having one of its ends fastened to the normally upper portion (Fig. 2) of door 11 and having its other end pivotally mounted on receiver 10. The hinge members 15 are each insulated from other conducting portions of the receiver 10, and are connected through leads 16 to the radio frequency input terminals on the receiver chassis within the housing of receiver 10. Within the door 11, the hinge members 15 are respectively connected to suitable conductors and to two snap fastener members 17 and 18 mounted on the inner side of the door 11. That is, the snap fasteners 17 and 18 are on that side of the door 11 adjacent the control knob 12 when the door 11 is closed.

Snap fastener elements 30 and 31 complementary to the snap fastener members 17 and 18 on the door 11 are carried on one end of a relatively wide tape or web member 19 along the respective edges of which two insulated conductors extend. These two conductors are connected to such complementary snap fastener elements 30 and 31 at the one end of the tape 19, and at the other end of the tape 19 those two conductors are respectively connected to snap fastening elements 20 and 21, supported on that other end of the tape. The same distance lies between the snap fastening elements 20 and 21 and between the snap fastening elements 17 and 18, and likewise between the snap fastening elements 30 and 31 on the tape 19 complementary with the snap fastening members 17 and 18. The snap fastening members 20 and 21 on the end of the tape 19 remote from the receiver 10 are, as may be best seen in Figs. 3 and 4, arranged to snap onto a pair of complementary snap fastener members 22 and 23, on a loop antenna structure 24. The loop an-

tenna structure 24 comprises a body of dielectrical insulating material upon, or preferably within, which a loop antenna is arranged with the ends of the looped conductor connected respectively to the snap fastener elements 22 and 23. The body of the antenna structure 24 carries, in addition to the snap fastener elements 22 and 23 which act as electrical terminals for the loop, supporting snap fastener elements 25 which are suitably spaced to fasten to complementary snap fastener elements 26 supported on the door 11 of the receiver 10.

Suction cups 27, each having a snap fastener element complementary to the snap fastener element 25 on the loop antenna structure 24, may be snapped onto the loop antenna structure to support it upon any smooth dielectric surface such as the window 28 of a metal or shielded vehicle within which the receiver 10 is disposed.

When the receiver is so arranged, with the antenna structure 24 mounted by means of suction cup 27 on a window 28 and connected through the tape with the radio frequency terminals 17 and 18 on the door 11 of the receiver 10, the receiver may be operated by means of the knobs 12, the antenna 24 being positioned for good reception of radio frequency energy in the shielded structure.

When the receiver is in a different location where it is not surrounded by conductive walls such as are usually encountered in vehicles, the ends of the tape 19 may be detached respectively from the antenna structure 24 and the radio frequency terminals 17 and 18 on the door 11, and the antenna structure 24 may be fastened on the inside of the door 11 by snapping together the cooperating snap fastener elements 25 and 26, and the cooperating radio frequency terminals 17, 18, 22 and 23. The tape 19 may be stowed in a suitable place within the housing of the receiver 10.

When the loop antenna structure 24 is so supported on the inside of the door 11, the receiver being in a position surrounded by conductive walls, the loop structure 24 is in a favorable position for the reception of radio frequency energy, since the door 11 is of dielectric or insulating material, and since the door carries the loop structure 24 at a substantial distance from any metal portion of the radio apparatus within the housing of the receiver 10.

It may be desired to make the housing of the receiver 10 except door 11 of light metal, such as magnesium or aluminum, and in that case the positioning of the antenna structure 24 upon the inside of the door 11 in its raised position is exceptionally desirable to maintain the antenna 24 away from any shielding and damping effect which is otherwise produced by the conductive metal housing of the receiver 10 on the loop antenna. If the housing of the receiver 10 is made of metal, and if the loop is mounted on or within that metal housing, the pickup of radio frequency energy would be so small as to be useless, and it is then highly desirable to mount the loop as described in accordance with the present invention.

When the loop antenna structure 24 is mounted in accordance with this invention on the door 11, the only metal parts of the receiver 10 being those provided in connection with the radio apparatus carried within the housing of the receiver, the pickup of radio frequency energy by the loop structure 24 is at least twice that obtained when the loop is mounted on or within the housing of the receiver 10 in the normal

fashion and relatively near the metal chassis of the receiver.

When the loop antenna structure 24 is mounted on the inside of the door 11, as described, a handle 29 provided on the upper surface of the housing of the receiver 10 is readily accessible for the purpose of carrying the receiver with the lid 11 in the open position, so that the receiver may be thus carried while it is operating.

When it is desired to discontinue operation of the receiver, one of the knobs 12 is adjusted to deenergize the receiver and the door 11 is moved over the handle 29 and toward the front of the housing of the receiver 10 and downward to cover the knobs 12, where it may be locked in position by suitable locking means. By the provision of the long armed hinge members 15, which are pivoted on the housing of the receiver 10 at points on an axis extending substantially through the handle 29, the door 11 clears the handle 29 readily. That is, the hinge members 15 are sufficiently long that they clear the upper surface of the housing of the receiver 10 by a distance such that the handle 29 may be provided of relatively large size for easy carrying of the receiver. This is so since the hinge members 15 are pivotally mounted on the receiver at a point substantially in the plane of the upper face of the receiver and at a point lying substantially midway between vertical substantially parallel faces of the receiver.

When it is desired to use the receiver 10 illustrated in Fig. 2 in its closed position, the door 11 is raised and pushed to its position shown in Fig. 1 back of the handle 29, where it is in stable equilibrium and where it lies in a substantially vertical plane a substantial distance behind the plane of the control panel including the knobs 12 and the tuning dial 13 and speaker located behind apertured area 14. With the door 11 in that position, the set may be operated by the knobs 12, so long as it is in a position where it is not surrounded by a conductive shielding wall such as in a train or automobile.

If the receiver 10 is to be used within an enclosure where some shielding is experienced, the loop structure 24 is unsnapped at the door 11 and the tape 19 removed from the place where it is stored within the receiver 10. One end of the tape 19 is snapped onto the snap fastener elements or radio frequency terminals 17 and 18 on the door 11, and the other end of the tape 19 is snapped onto the snap fastening elements forming the electrical loop terminals on the loop structure 24. Suction cups 27 are removed from a position within the housing of receiver 10 wherein they are stowed, and they are snapped on the snap fastening elements 25 on the loop structure 24. The loop structure 24 is then fastened by means of the suction cup 27 to a smooth surface such as the window 28, whereupon the radio receiver 10 may be made to operate by adjustment of the knobs 12.

It is to be noted that when the structure 24 is mounted on a surface such as the window 28 by means of a suction cup 27, the same side is presented to the view of an operator of the receiver 10, as is presented by the loop structure 24 when it is mounted on the door 11. A suitably modest and attractive design is applied to that side of the loop structure 24, in keeping with the appearance of the remainder of the receiver 10. On the other side of the loop structure 24, as illustrated in Figs. 3 and 4, a more elaborate design of an advertising nature may be placed, that side being ob-

scured by the door 11 when the loop 24 is mounted thereon, but being visible through the window 28 from outside the vehicle when the loop 24 is mounted on the window 28.

While particular embodiments of the present invention have been shown and described, it will be obvious to those skilled in the art that changes and modifications may be made without departing from this invention in its broader aspects, and, therefore, the aim in the appended claims is to cover all such changes and modifications as fall within the true spirit and scope of this invention.

I claim:

1. In radio apparatus comprising a case enclosing a radio circuit having two terminals and a door closing at least a portion of one side of said case, the combination of long arm hinge members permanently fixed substantially perpendicularly to one edge of said door and permanently secured pivotally on an adjacent side of said case about an axis lying substantially parallel to said one side of said case and substantially midway of said adjacent side of said case, a handle substantially centrally located on said adjacent side of said case, said door being arranged to open on said hinge members away from said case a distance sufficient to move over said handle to a position on the other side of said handle from said one side of said case, a unitary loop antenna structure having snap fastening means connected in circuit therewith, snap fastening means complementary to said snap fastening means of said antenna structure arranged on that side of said door adjacent said case when said door is closed, means for connecting said snap fastening means of said door with said two terminals of the radio circuit through said hinge members, and a flexible two conductor transmission line having snap fastening means on the ends thereof respectively complementary to said snap fastening means on said antenna structure and said snap fastening means on said door, said line being detachably connected between said door and said antenna structure and providing connections through said snap fastening means, line, and hinge members between said antenna structure and said radio circuit terminals, said two first mentioned snap fastening means being arranged so that said antenna structure may be supported on said door and connected to said two terminals by cooperation between said two first mentioned snap fas-

tening means when said line is detached from the door and antenna.

2. In radio apparatus comprising a case enclosing a radio circuit and a door closing at least a portion of one side of said case, the combination of long armed hinge members permanently fixed to said door and permanently secured pivotally adjacent another side of said case on a line spaced a substantial distance from said one side of said case, said door being arranged to open upon said hinge members away from said one side of said case and to move over said other side of said case to a position removed from one side of said case, an antenna, means for detachably securing said antenna on said door, said means comprising complementary snap-fastening means on said door and said antenna, means for connecting said antenna with said radio circuit through said securing means and said hinge members, means for electrically connecting said snap fastening means together when said antenna is detached from said door thereby to connect said antenna with said radio circuit, and means for quickly attachably and detachably securing said antenna on a surface spaced from said apparatus, the last means having snap fastening means complementary to said snap fastening means on said antenna thereby to secure said last securing means on said antenna after detachment of said antenna from said door.
